UNITED STATES PATENT OFFICE.

LYLE F. GRAY, OF BEAVER DAM, AND LYLE WEDGE AND ERNEST GIESE, OF WAUPUN, WISCONSIN, ASSIGNORS TO PARAMOUNT HOSIERY FORM DRYING CO., OF CHICAGO, ILLINOIS, A CORPORATION OF ILLINOIS.

HOSIERY DRYING AND SHAPING STRUCTURE.

1,279,332.

Specification of Letters Patent. Patented Sept. 17, 1918.

Application filed April 26, 1918. Serial No. 230,983.

To all whom it may concern:

Be it known that we, LYLE F. GRAY, a citizen of the United States, residing at Beaver Dam, in the county of Dodge and State of Wisconsin, and LYLE WEDGE and ERNEST GIESE, citizens of the United States, residing at Waupun, in the county of Dodge and State of Wisconsin, have invented certain new and useful Improvements in Hosiery Drying and Shaping Structures, of which the following is a specification, reference being had thereto to the accompanying drawing.

This invention relates to hosiery drying and shaping structures, and has more especial reference to fabric-holding instrumentalities therefor whereby shrinking or creeping of the hosiery on a drying and shaping form is reduced to a minimum if not entirely prevented.

It is well known in the art that hosiery—after it has come from the centrifugal or "whizzer" (as it is sometimes called) and has been placed upon drying forms—has a natural tendency to shrink somewhat, and this usually occurs during the first stages of the drying operation and continues until sufficient of the moisture in the fabric is evaporated so that such fabric may, then, set or become fixed. It has been found in actual practice that if the fabric is nicely positioned on the form and properly stretched thereon and, then, for a moment or so manually or otherwise maintained in such stretched condition, the drying heat applied by the drying-form to the fabric will set it, after which its shrinkage will not be to any degree substantial.

The present invention is predicated upon the discovery that by the provision of a proper type of holding instrumentality on the form, it will operate to engage the internal surface of the stretched hosiery-article and hold it until it is properly set and becomes fixed in its stretched condition.

To that end, we have provided a new instrumentality, the same being conveniently mounted on opposite sides of a hosiery-drying and shaping form, the latter being of the type which is hollow to contain a heating medium and made of metal to impart its drying heat rapidly and effectively to the article thereon to accomplish a drying of the hosiery and, at the same time, effect a

shaping, setting and finishing of the same, 55 the latter following from the fact that the fabric becomes and remains fixed in the condition to which it is stretched, the form itself determining the dimensions, contour and shape of the ultimate product. 60

In the accompanying drawings, we have illustrated several embodiments and utilizations of our invention; and it will be obvious therefrom that other embodiments and utilizations may be made (and even 65 modifications of those disclosed) without departing from the spirit of the invention or sacrificing any of its advantages; wherefore, it is to be noted that the embodiments thus revealed are intended to be merely 70 illustrative.

In these drawings:

Figure 1 is a view in elevation of a drying and shaping form with our invention applied thereto; 75

Fig. 2 is a fragmentary view in edge elevation of the same;

Fig. 3 is a view in transverse section on the line 3—3, Fig. 2;

Fig. 4 is a fragmentary view, on an enlarged scale, of a section of the form with the fabric-engaging instrumentality applied; 80

Fig. 5 is a view similar to Fig. 1, but with a different type of fabric-engaging instrumentality applied, the form in this instance 85 having a half-hose mounted thereon, the latter being broken away at one point to show the relation of the fabric-engaging instrumentality with the hose;

Fig. 6 is a fragmentary view in edge elevation showing the type of fabric-engaging instrumentality illustrated in Fig. 5; 90

Fig. 7 is a detail view, on an enlarged scale, of the fabric-engaging instrumentality detached from the form; 95

Fig. 8 is a view in transverse section on the line 8—8, Fig. 6;

Fig. 9 is a fragmentary view on an enlarged scale, showing the wall of the form in section and likewise the fabric-engaging 100 instrumentality;

Fig. 10 is a fragmentary view of a hosiery-drying and shaping form with a still different type of fabric-engaging instrumentality applied thereto; 105

Fig. 11 is a view in transverse section on the line 11—11, Fig. 10;

Fig. 12 is a fragmentary view of the form

with still another type of fabric-engaging instrumentality applied thereto; and

Fig. 13 is a view in transverse section thereof on the line 13—13, Fig. 12.

- 5 In these drawings, the reference-character 1 designates a hosiery-drying and shaping form, which may be of any preferred construction and shape, but which, in this instance, is preferably of the general type 70
10 illustrated in United States Patent No. 1,207,496, granted December 5, 1916. It is hollow, as at 2, to contain a heating medium whereby heat is thereby applied to the internal surface of the fabric of the hosiery, 75
15 designated generally by the reference-numeral 3. This form has fabric-smoothing and flattening sides 4 which, in this instance, are shown as arc-shape and as merging into reduced or crease-forming edges 5. The 80
20 form is provided with a base 6 by which it is secured to a pipe 7 or other instrumentality for conveying a thermal fluid from a suitable source of supply to the interior 2 of the form.
25 Mounted on opposite sides of the form, and at a predetermined distance above the base 6 is a fabric-engaging and holding instrumentality 8, this being, preferably and as shown, of less width than that of the form 85
30 1 so that the two engaging instrumentalities do not entirely encompass the form.

The particular type of instrumentality shown in the embodiment illustrated in Figs. 1 to 4 is a piece of fabric composed of a 90
35 base 9 and a pile 10 which, in this instance, is of a character to smooth down flat when rubbed in one direction but which, when rubbed in the other direction, tends to stiffen, stand out, and offer more or less resistance or friction. As a result of considerable experimenting, we have found that 95
40 plush or the like—which includes the base 9 and the pile 10 of the kind described—constitutes a very desirable type of fabric for 100
45 our purpose. Thus when applied to the sides of the form, as shown, the “boarding” of the hosiery, that is, placing the hosiery on the form, is not at all interfered with while 105
50 the hosiery is being stretched down over the holding instrumentality 8; but, the moment that the stretching motion ceases, the pile 10 effectually opens out (so to speak) and firmly retains the fabric against upward shrinkage or creeping. It is to be understood that, in the boarding operation referred to, the fabric of the hosiery is 110
55 stretched longitudinally so that its lower end will approximate one or another of the limiting lines or marks 11 (Fig. 1). The 115
60 construction and shape of the form are such as to approximate the circumferential dimension of the ultimate product; and to this end the fabric is, while being boarded, stretched by the form to the dimension of the ultimate 120
65 product circumferentially; and it is also 125

stretched by the boarder to the longitudinal dimension of the ultimate product when its end approximates the marking-line 11. By reason of the quickness and intensity of the action of the heat of the form on the wet fabric, the latter is rapidly and permanently set in its stretched condition so that it finishes not only at the circumferential dimensions mentioned but, by means of the holding instrumentality 8, is retained and set 75
70 at the longitudinal dimension also. During this stretching and setting operation, the sides 4 contribute to iron and flatten down the internal surfaces of the sides of the fabric, while the reduced edges 5 contribute 80
85 to effect an internal crease-forming at the edges of the hosiery.

By reason of the fact that heat more or less affects most cementitious substances, and especially where these are utilized as a binder 90
95 between metal and a different substance (such as fabric), we find it advantageous to secure the fabric of the holder 8 to the sides of the form by liquid-glass 12. This substance is conveniently and quickly applied and dries rapidly when the fabric of the holder 8 is mounted on the form while the latter is hot or heated. Besides, liquid-glass, when hardened, becomes a good conductor 95
100 of heat and, thus, reduces the normal tendency of the holder 8 to be heat-resistant. In other words, the binding between the holder 8 and the form tends to convert the holder from a non-conductor of heat into an effective conductor thereof. This is desirable because the drying of the wet hosiery, at the point where it is in engagement with the holder 8, would be retarded were it not that the holder itself becomes a heating surface for the reasons explained. 105

It has been found in practice that the stretching of the wet hosiery down over the holder 8 tends to damage its upper edge or end; hence, various protecting instrumentalities have been proposed. But we have found in practice that an effective protector consists of a strip or plate 13 of any appropriate material, which in this instance is, preferably, paper or the like. The paper is cemented to the sides of the form above the holder 8 but having its lower ends 14 overlapping the upper end 15 of the holder. For the reasons explained in connection with the holder, the liquid-glass binder used to secure the protector 13 to the form tends to 110
115 make it a good conductor of heat also. The overlapping end 14 effectively covers and protects the upper end 15 of the holder. The protector 13 may be of metal, if desired; or, in fact, any other suitable material. 120
125

If, for any reason, it be desired not to use the protector 13, this may be omitted and merely the holder 8 be employed, as illustrated in the embodiment of Figs. 5 to 9. In this instance, also, we have shown the 130

holding instrumentality 8 as provided with perforations 16, these being to permit the heat to pass directly from the surface of the ironing and shaping sides 4 into the fabric of the hosiery. This is a modification which may in some instances be found to possess advantageous features.

In Figs. 10 and 11, we have shown an embodiment utilizing a mesh-fabric 17, this 10 presenting protruding portions 18 which are adapted to perform the equivalent function of the pile 10 of the plush holder 8, though perhaps not so effectually.

In Figs. 12 and 13, we have shown a 15 fabric-engaging and holding instrumentality 19 composed of a fabric like carpet. This has also been found to be an effectual holding instrumentality, though its character of weave is such as to make it possibly not so 20 desirable as other materials. Besides, it is comparatively thick and, thus, prevents the heat of the form from penetrating the fabric as quickly; but to facilitate such penetration of the heat, we may provide the holder 19 25 with a series of perforations 20.

From the foregoing, it will be perceived that we propose the mounting on the side of a hosiery-drying and shaping form of a 30 type of hosiery-engaging and holding instrumentality which has the desirable attribute of engaging the internal surface of the fabric and gripping the same so that the fabric of the hosiery, being then in a stretched condition, will remain in such 35 stretched condition until it becomes fixed or set.

In practice, it has been found that where the fabric of the hosiery is stretched in the manner and to the dimensions referred to, 40 the general finish of the external surface of the fabric is appreciably improved. Besides, by reason of the fact that the fabric is held in close contact with the heating surface of the form, the latter more quickly performs 45 its function of drying the hosiery and, thus, the efficiency of the form itself is greatly increased. The hosiery is finished at a uniform length because, by the different types of instrumentalities here revealed, such 50 hosiery is prevented from creeping and shrinking while drying.

What we claim is:

1. A drying and shaping structure including a form upon which hosiery is stretched 55 to the dimensions of the ultimate product, and means for maintaining the hosiery in a stretched condition while drying on the form and while being set during the drying, such maintaining means comprising a fabric 60 securable to the form and composed of a body-portion and a pile outstanding therefrom.

2. A drying and shaping structure including a form upon which hosiery is 65 stretched to the dimensions of the ultimate

product, means for maintaining the hosiery in a stretched condition while drying on the form and while being set during the drying, such maintaining means comprising a fabric securable to the form and composed of a 70 body-portion and a pile outstanding therefrom, and a protecting instrumentality overlapping a portion of the fabric.

3. A drying and shaping structure including a form upon which hosiery is stretched 75 to the dimensions of the ultimate product, means for maintaining the hosiery in a stretched condition while drying on the form and while being set during the drying, such maintaining means comprising a fabric securable to the form and composed of a body-portion and a pile outstanding therefrom, a 80 protecting instrumentality including a strip of paper overlapping a portion of the fabric, and a binder between the protector and the 85 form.

4. A drying and shaping structure including a form upon which hosiery is stretched to the dimensions of the ultimate product, means for maintaining the hosiery in a 90 stretched condition while drying on the form and while being set during the drying, such maintaining means comprising perforated fabric mounted at opposite sides of the form and of less width than that of the form, and 95 a binder between the fabric and the form including liquid-glass.

5. A fabric-holding instrumentality for a drying and shaping form, comprising a body-portion which includes fabric having 100 a fabric-gripping surface engageable with the internal surface of hosiery superposed upon the form, and liquid-glass which constitutes a binder and heat-conductor between the form and the fabric. 105

6. A fabric-holding instrumentality securable to drying and shaping forms comprising a strip of fabric secured to the form, and a heat-conducting binder between the 110 form and the fabric.

7. A fabric-holding instrumentality securable to drying and shaping forms comprising a strip of fabric secured to the form, a heat-conducting binder between the form and the fabric, and a fabric-protector 115 secured to the form and overlapping a portion of the fabric.

8. A fabric-holding instrumentality securable to drying and shaping forms comprising a strip of fabric secured to the form, 120 a heat-conducting binder between the form and the fabric, and a fabric-protector including a strip of paper secured to the form and overlapping a portion of the fabric.

9. A hosiery-holding device securable to 125 the external surface of a drying and shaping form, including a piece of fabric comprising a body-portion and a pile outstanding therefrom.

10. A hosiery-holding device securable to 130

the sides of a drying and shaping form comprising a strip of fabric composed of a body-portion and a pile, and securable to the form by a cementitious mass including liquid-glass, and a protector also securable to the form by a cementitious mass including liquid-glass and overlapping a portion of the fabric.

11. A hosiery-holding device securable to the sides of a drying and shaping form comprising a strip of fabric composed of a body-

portion and a pile, and securable to the form by a cementitious mass including liquid-glass, and a protector including paper also securable to the form by a cementitious mass including liquid-glass and overlapping a portion of the fabric. ¹⁵

In testimony whereof, we have hereunto affixed our signatures.
